His Attorney.

UNITED STATES PATENT OFFICE

2,056,140

SEAL FOR ELECTRIC DISCHARGE DEVICES

Albert Amillac, Belfort, France, assignor to General Electric Company, a corporation of New York

Application July 31, 1930, Serial No. 472,008
In France September 4, 1929

8 Claims. (Cl. 250—27.5)

My invention relates to means for producing a gas-tight seal between the walls and electrode leads of an electric discharge device, such as a vapor rectifier or the like, and has for its principal object the provision of an improved seal which can be relied upon to prevent the leakage of air into the evacuated vessel of the device, to support the electrodes and to insulate the electrode leads from the wall of the evacuated vessel.

In the construction of large vapor electric rectifiers, great difficulty in producing a gas-tight seal between the electrode leads and vessel walls has been heretofore encountered. It has been attempted to interpose a body of fused basalt or like vitreous material between the vessel wall and electrode lead for the purpose of supporting the electrode and producing a hermetical seal between the vitreous material and the lead. As a result of such attempts, it has been found impractical to join the vitreous insulating body directly to the lead because of oxidation of the lead during the attachment of the vitreous material to the lead, this oxidation tending to produce fragility and porosity at the juncture between the vitreous material and metal.

In accordance with my invention, this difficulty is obviated by the provision of a layer of reducing or neutral material such as copper, nickel, varnish, lacquer or the like, at the juncture between the vitreous material and metal and by so rearranging the various parts of the seal that the juncture between the metal and vitreous material is not subjected to the rapid temperature changes heretofore encountered. As a further precaution against leaks, this juncture is provided at its outer edge with an additional seal including mercury or other suitable sealing material.

My invention will be better understood from the following description when considered in connection with the accompanying drawing, and its scope will be pointed out in the appended claims.

The drawing is a sectional view of an insulation seal wherein my invention has been embodied.

For the sake of simplicity, it is assumed that the insulating substance is fused basalt but it goes without saying that this body could be of any suitable vitreous material. The joint, the tightness of which is to be insured, is that between the metal member 1 and the insulator 2. The line along which the surface of this joint protrudes from the apparatus is covered with an

annular joint 3 of plastic material, on which rests rigid metal element 4 which is likewise ring-shaped and which is properly clamped on the plastic joint 3 by means of screws 5, through intermediate elastic washers 6. The reaction of the pressure exerted by screws 5 rests, through the intermediate ring 9, on two semi-rings 7 which fit in a groove 8 that is provided in part 1. Ring 9 is also equipped with stop pins 10, with nuts and elastic washers, which press a cover 11 on cylinder 12, below which a plastic joint 13, similar to joint 3, is located, which joint is properly squeezed against the upper surface of the basalt insulator 2.

In this manner an annular chamber is obtained which is limited as follows: Part 1, upper surface of insulator 2, cylinder 12, and finally cover 11. In this annular chamber a certain quantity of mercury 14 is introduced which covers entirely the plastic joint 3. There is provided in this manner a joint which in itself is quite hermetical and which answers the purpose even if the contact surface between part 1 and the basalt insulator becomes permeable to air or mercury.

A float 15, which is visible from the outside and which comprises a graduation, permits of controlling the mercury level which covers the joint.

The improved arrangement also has the purpose of reducing the heat transmission through conduction between the anode-carrier rod 16 on which anode 17 is screwed, and insulator 2, in order to lower the temperature of this insulator and to reduce the speed at which it heats up.

To this end, the rod 16 does not rest directly on insulator 2, but on an intermediate metallic sleeve 1, which is introduced between the anode carrier rod 16 and the basalt. Besides, the weld 18, through which rod 16 and sleeve 1 are made integral with each other, is well above the upper level of insulator 2. Finally, space 19, which is connected with the vacuum system, is provided between the anode-carrier rod and sleeve 1. Through this arrangement, the temperature drop between the anode 17, which constitutes the heat source of the system, and the top of the insulator 2, which is in contact with sleeve 1, is duly increased.

What I claim as new and desire to secure by Letters Patent of the United States is:—

1. In a seal for electric discharge devices, the combination of a metal sleeve provided at one of its ends with a non-oxidizing coating, an electrode lead attached to the other end of said

sleeve and spaced from said sleeve throughout the remainder of its length, a body of vitreous material joined to said sleeve through said non-oxidizing coating to form a seal for said lead, and 5 additional sealing means for said lead including an annular member of plastic material and means to maintain said member in contact with said body and said sleeve at the jointure of said body and sleeve.

10 2. In a seal for electric discharge devices, the combination of a metal sleeve provided at one of its ends with a non-oxidizing coating, an electrode lead attached to the other end of said sleeve and spaced from said sleeve throughout the remainder 15 of its length, a body of vitreous material joined to said sleeve through said non-oxidizing coating to form a seal for said lead, and additional sealing means for said lead including a member of plastic material in contact with the jointure of 20 said body and sleeve and a body of mercury covering entirely said member of plastic material.

25 3. In a seal for an electrode of an electric discharge device, a body of vitreous material, means including a metallic member to join said electrode to said body, a sealing member of plastic material, and means to press said sealing member against said body and said metallic member at the jointure of said body and said metallic member.

30 4. In a seal for electric discharge devices, the combination of a metal sleeve, an electrode lead attached to one end of said sleeve, a body of vitreous material joined to said sleeve at the other end thereof, an annular member of plastic material, and means to maintain said member in contact with said body and said sleeve at the jointure of said body and sleeve.

35 5. In a seal for electric discharge devices, the combination of an insulation member, an anode lead and a metal sleeve joined at one of its ends 40 to said lead and at the other of its ends to said member, and additional sealing means including an annular member of plastic material super-posed on the juncture between said member and said sleeve, means comprising a cylindrical member to press tightly said annular member against said jointure, a second annular member of plastic material surrounding said first-named annular member, means comprising a cylindrical member separate from said first-named cylindrical member to press tightly said second-named annular member against said insulation member to form an annular chamber between said second-named cylindrical member and said sleeve, and a body of mercury in said annular chamber covering said first-named annular member and in contact with said second-named annular member.

45 6. In a seal for electric discharge devices, the combination of a body of vitreous material, an anode lead, a metal sleeve attached at one of its ends to said lead and joined at the other of its ends to said body at one end of said body, and additional sealing means for said lead including

a member of plastic material in contact with the jointure of said body and sleeve, means comprising a cylindrical member to press tightly said annular member against said jointure, a second annular member of plastic material surrounding said first-named annular member, means comprising a cylindrical member separate from said first-named cylindrical member to press tightly said second-named annular member against said insulation member to form an annular chamber between said second-named cylindrical member and said sleeve, and a body of mercury in said annular chamber covering said first-named annular member and in contact with said second-named annular member. 15

7. In a seal for electric discharge devices, the combination of a metal sleeve, an electrode lead attached to one end of said sleeve, a body of vitreous material joined to said sleeve at the other end of said sleeve, and additional sealing means 20 for said lead including a member of plastic material in contact with the jointure of said body and sleeve, means comprising a cylindrical member to press tightly said annular member against said jointure, a second annular member of plastic 25 material surrounding said first-named annular member, means comprising a cylindrical member separate from said first-named cylindrical member to press tightly said second-named annular member against said insulation member to form an annular chamber between said second-named cylindrical member and said sleeve, and a body of mercury in said annular chamber covering said first-named annular member and in contact with said second-named annular member. 30

8. In a seal for electric discharge devices, the combination of a metal sleeve, an electrode lead attached to one end of said sleeve and spaced radially therefrom throughout the remainder of the length of said sleeve, a body of vitreous material joined to said sleeve at the other end of said sleeve, the portion of said sleeve extending from the joint between said body and said sleeve to that portion of the sleeve to which the electrode lead is attached being of substantial length to increase the temperature drop between said electrode and said body, and additional sealing means for said lead including a member of plastic material in contact with the jointure of said body and sleeve, means comprising a cylindrical member to press tightly said annular member against said jointure, a second annular member of plastic material surrounding said first-named annular member, means comprising a cylindrical member separate from said first-named cylindrical member to press tightly said second-named annular member against said insulation member to form an annular chamber between said second-named cylindrical member and said sleeve, and a body of mercury in said annular chamber covering said first-named annular member and in contact with said second-named annular member. 40
